CLAIM

The ornamental design of a vest for an animal, as shown and described.

DESCRIPTION

FIG. 1 is a top, front, right perspective view of a vest for an animal, showing my new design.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof; and,

FIG. 7 is a bottom plan view thereof.

In the drawings, the features shown in broken lines form no part of the claimed design.
